UNITED STATES PATENT OFFICE.

CHARLES J. BAKER, OF PHOENIXVILLE, PENNSYLVANIA.

UNDERGARMENT.

1,081,196.

Specification of Letters Patent.

Patented Dec. 9, 1913.

Application filed February 28, 1913. Serial No. 751,303.

To all whom it may concern:

Be it known that I, CHARLES J. BAKER, a citizen of the United States, residing in Phoenixville, Pennsylvania, have invented 5 certain Improvements in Undergarments, of which the following is a specification.

My invention relates to under garments and consists of an improved form of garment known as union garments.

10 The chief object of my invention is to provide a garment of the above mentioned class which will have an open crotch and open rear portion and means for normally keeping the said open crotch and rear portion closed.

Another object of my invention is to produce a garment of the above described type which can be quickly and cheaply manufactured and which will be durable and 20 comfortable to the wearer.

These objects I attain in the following manner; reference being had to the accompanying drawings in which,

Figure 1, is a view of a flattened tubular fabric from which the garment is preferably cut; Fig. 2, is a view of the main portion of the garment after the same has been cut from the tube shown in Fig. 1 and reflatened on the line $a-a$ Fig. 1; Figs. 3 and 4, are views of gussets which are inserted in the leg portions and which are cut in a particular manner; Fig. 5, is a view of an insertion which I preferably use; Fig. 6, is a rear view of the main body portion as shown in Fig. 2; Figs. 7 and 8, are front and rear views respectively of my improved garment; Fig. 9, shows another manner of cutting the main portion of my garment; and Fig. 10, shows another manner of forming the leg and crotch gussets.

In forming my improved garment from the fabric shown in Fig. 1 the latter is cut on the lines 1 and 2 through both thicknesses thereby separating the main portion 46 of the garment from the gusset portion. The fabric is then split along one edge from the point 1 to the point 3 and along the opposite edge from 2 to 4 and then through both thicknesses from 4 to 5. The neck and 50 arm portions are cut at the top of the tube in any form or shape desired in the usual manner.

The leg and crotch gussets are produced by cutting through both thicknesses of the 55 fabric on the lines 6, 7, 8 and 9, 10, 2, and

the insert or gusset section as shown in Fig. 5 may be cut from the waist fabric remaining as clearly shown by the triangle b . Each of the gussets made in the above mentioned manner will be divided into two sections by a cutting on the line 7-8 and 7 a -8 a and the division will extend down from its upper end.

In assembling the garment, the sides 11 and 12 of the triangular gusset section are 65 sewed to the edges 13 and 14 of the main fabric formed by the splitting of the fabric from 1 to 3 as before stated and so that the apex 15 is at the point 3 as clearly shown in Fig. 7. The edge 9 to 10 of the 70 leg gusset shown in Fig. 4 is then sewed to the edge of the triangular gusset section or insert so that the point 10 of the gusset is substantially coincident with the point 16 of the said triangular insert. The edge 10, 75 17 of the gusset shown in Fig. 4 is then sewed to the remaining portion of the edge 14 and the edge 6, 7 of the leg gusset is sewed to the portion 18, 19 formed by the cut 4 to 5 and so that the curved edge 7 80 to 8 extends on the inside of the double thickness fabric as shown by the curved dotted line in Fig. 8. The edge 6, 20, of the said latter gusset is then sewed to the edge 21 formed by the cutting of the fabric 85 from the point 2 to 4. The gusset shown in Fig. 3 is then inserted by sewing the edge 6 a , 20 a to the edge 22, and the edge 6 a to 7 a to the edge 18 to 23 which were also formed by the cutting from 4 to 5. The edge 9 to 10 a is then sewed to the lower edge or piece 90 of the triangular insert b so that the point 10 a is at the point 24 of the said insert. The edge 10 a to 17 a is then sewed to the remaining portion of the edge 13. By the above 95 arrangement the lowest portions of the edges formed by the cutting from 9 to 8 and from 9 a to 8 a will be coincident and the points 8 and 8 a will be substantially coincident.

It will thus be seen that since the edges 8 a -9 a and 8-9 flare upwardly and continue to increase their degree of overlap in the front of the garment, and since the edges 8-7 and 8 a -7 a extend upwardly in the rear in an overlapped position, a garment made 100 in accordance with my invention will be close-fitting at the crotch portion owing to the fact that the gussets are sewed to the bottom of the triangular insert in the manner heretofore described that the free edges 110

from 8 to 9 and from 8^a to 9^a of the leg gussets will telescope and tend to keep the crotch portion closed under normal conditions as is clearly shown in Fig. 7, and, as the portions of the gussets bounded by the curved edges form the overlapping flaps in the rear, it will be readily seen that, as they spring from the crotch portion, they will normally tend to form a proper closure for the rear 10 opening of the garment.

In the form of cutting shown in Fig. 9 the edges which result from the cutting on the line 4, 5 of Fig. 1, are eliminated. In this case the line 6, 7 is sewed directly to the 15 main portion of the garment in the same position shown from 18 to 19 in Fig. 8.

In Fig. 10 I have shown a leg gusset and the triangular section or insert formed in one piece and this construction can be employed if so desired. 20

I claim:

1. A union garment made from a tubular fabric cut at its front and rear throughout a portion of its length to form leg portions; 25 gussets inserted in the leg portions, each of said gussets being divided for a portion of its length downwardly from its upper end and having edges secured respectively to the edges formed by the front and rear cuts of the fabric, one of the portions formed by the division of each gusset extending upwardly and being secured to the front of the fabric, the other of said latter portions extending upwardly and being secured to the rear of 30 said fabric.

2. An open crotch union garment made from a tubular fabric cut at its front and rear throughout a portion of its length to form leg portions; a gusset inserted in each 40 leg portion, each of said gussets being divided for a portion of its length downwardly from its upper end and having edges secured respectively to the edges formed by the said front and rear cuts of the fabric, one of the 45 portions formed by the division of each gusset extending upwardly and being secured to the front of said fabric in a position overlapping the other, the other of said portions extending upwardly and being secured to 50

the rear of said fabric also in an overlapped position.

3. An open crotch union garment made from a tubular fabric cut at its front and rear throughout a portion of its length to form leg portions; a gusset inserted in each 55 leg portion, each of said gussets being divided for a portion of its length downwardly from its upper end and having edges secured respectively to the edges formed by the said forward and rear cuts of the fabric, one of 60 said portions formed by the division of one of the gussets terminating in an angular section and having its edges secured to the upper part of the edges forming the front leg portions of the garment, another portion of 65 each gusset formed by the division extending upwardly and being secured to the rear of the said fabric in a position overlapping the other, said angular portion and a portion formed by the division of the other gusset extending upwardly in an overlapped position, the latter portion being also secured to the said fabric. 70

4. An open crotch union garment made from a tubular fabric cut at its front and 75 rear throughout a portion of its length to form leg portions; a crotch gusset inserted in each leg portion, each of said gussets being divided into two sections partway down from its upper end and having edges secured 80 respectively to the edges formed by the said front and rear cuts, one of said sections in one gusset having a free edge coincident at the crotch with a free edge of one of said sections of the other gusset, said free edges 85 flaring upwardly in overlapped positions, said latter sections being secured to the front of the fabric, the other of said sections having free edges extending from the crotch upwardly in the rear, in overlapped positions 90 and being secured to the rear of the fabric.

In testimony whereof, I have signed my name to this specification, in the presence of two subscribing witnesses.

CHARLES J. BAKER.
